UNITED STATES PATENT OFFICE.

WILLIAM L. GUMPRECHT, OF NEW YORK, N. Y., ASSIGNOR TO NEPTUNE METER COMPANY, OF NEW YORK, N. Y., A CORPORATION OF NEW JERSEY

METER.

941,573.

Specification of Letters Patent. **Patented Nov. 30, 1909.**

Application filed April 3, 1909. Serial No. 487,728.

To all whom it may concern:

Be it known that I, WILLIAM L. GUMPRECHT, a citizen of the United States, residing in the borough of Manhattan, of the city of New York, in the State of New York, have invented certain new and useful Improvements in Meters, of which the following is a specification, reference being had to the accompanying drawing, forming a part hereof.

This invention relates to meters of the oscillating or nutating disk type in which the registering mechanism is actuated by a disk which oscillates or nutates in a disk chamber under the influence of the flow through such chamber of the liquid to be measured. In the operation of such meters it sometimes happens that a hard body of some kind, such as a small pebble, passes into the disk chamber and, lying between the face of the disk and the conical wall of the chamber into close contact with which the disk should come in its movements, prevents the proper movement of the disk. The movement of the disk is imparted to the registering mechanism through a disk spindle which co-operates with an arm on the driving spindle of the registering mechanism and is guided in its movement by contact with the head of such driving spindle. There being usually no provision for yielding between the disk spindle and the driving spindle, the result of such interference with the proper movement of the disk as above referred to is a breakage of some of the parts, usually a fracture of the disk.

It is the object of this invention to reduce the danger of breakage from this cause and to that end a yielding cushion is interposed between the disk and the driving spindle of the registering mechanism which will permit the disk to accommodate itself to a small hard body which may be interposed between it and the adjacent conical face of the disk chamber until such body is washed out.

The invention will be more fully explained hereinafter with reference to the accompanying drawing in which different embodiments thereof are illustrated and in which the figure is a view, partly in section and partly in elevation, of so much of a nutating disk meter as is necessary to enable the invention to be understood.

The disk casing comprising the upper part 55 *a* and the lower part *b*, is provided with the

usual diaphragm *c* and inlet and outlet ports and with a suitable seat *f* for the disk ball *g* which carries the nutating disk *h*. The disk spindle *i* projects through the upper disk casing *a* and co-operates with an arm *k* 60 on the lower end of the driving spindle *m* of the register mechanism. In the ordinary construction of meters of this type there is mounted above the arms *k* of the driving spindle a conical head against which the upper end of the spindle *i* rests in its movements, being guided thereby. Both the spindle and the guiding head are usually rigid so that there is no possibility of yielding, except in the disk itself, when a hard 70 body enters the disk casing and rests between the disk and the conical surface of the disk chamber.

In the embodiment of the present invention, which is illustrated in the figure of the drawing, however, the conical guide head *n* is not rigid but is mounted movably upon the flared lower end of a sleeve *o* which is secured upon the bearing sleeve *p* of the spindle *m*. The lower end of the sleeve *o* 80 forms an annular, preferably spherical seat *o'* upon which rests the suitably shaped annular guiding head *n*, a spring *r* being interposed between the lower plate *q* of the gear train and the upper end of the annular guiding head *n* to hold the latter yieldingly 85 upon its seat. It will now be seen that if a hard body is interposed between the lower conical surface of the disk chamber and the disk, so as to prevent the disk from moving 90 down into full contact with the conical surface at that point, the yielding cushion afforded between the disk spindle and the driving spindle by the yielding guiding head *n* will permit the disk spindle to yield 95 to the abnormal movement of the disk, the guiding head *n* being crowded up and to one side upon its seat *o'* and returning to its normal position as soon as the hard body has passed on through the disk chamber. It 100 will be understood, of course, that the annular guiding head *n* is conical interiorly, as well as exteriorly, so as to permit of its displacement upon its supporting sleeve *o* under abnormal conditions.

I claim as my invention:

1. In an oscillating or nutating disk meter, the combination with the disk casing, disk, disk spindle and register driving spindle provided with an arm to be engaged by 110

the disk spindle, of an annular guiding head for coöperation with the disk spindle, an annular spherical seat upon which said guiding head is movably supported and a spring holding the guide yieldingly upon its seat.

2: In an oscillating or nutating disk meter, the combination of the register driving spindle provided with an arm adapted to be engaged by the disk spindle, an annular

guiding head for coöperation with the disk spindle, a seat upon which the guiding head is movably supported and a spring holding the guide yieldingly upon its seat.

This specification signed and witnessed this 1 day of April, A. D., 1909.

WILLIAM L. GUMPRECHT.
